UNITED STATES PATENT OFFICE.

OTTO A. FREDERICKSON, OF WETHERSFIELD, CONNECTICUT, ASSIGNOR TO THE AMERICAN WIREMOLD COMPANY, OF HARTFORD, CONNECTICUT, A CORPORATION OF CONNECTICUT.

BRAIDING MACHINE.

Application filed June 9, 1925. Serial No. 35,917.

To all whom it may concern:

Be it known that I, OTTO A. FREDERICKSON, a citizen of the United States, residing at Wethersfield, county of Hartford, and State of Connecticut, have invented an Improvement in Braiding Machines, of which the following description, in connection with the accompanying drawings, is a specification, like characters on the drawings representing like parts.

This invention relates to braiding machines, and more particularly to novel means for causing the strands of yarn from the outer yarn carriers to pass under some of the inner carriers and over others.

Heretofore traversing arms have been extensively used in braiding machines to raise and lower the outer strands of yarn to cause the inner yarn carriers to pass alternately over and under the outer strands of yarn.

An object of the present invention is to increase the speed at which braiding machines may be driven and to reduce the maintenance cost, by disposing of the traversing arms used heretofore and substituting therefor a simpler construction that requires only a slight movement to direct the outer strands of yarn to the opposite sides of the inner carriers.

One important feature of the present invention, therefore, resides in noses that are pivotally mounted upon the inner carriers, and in pins which are supported in the path in which the noses travel to engage and shift them.

In some cases it may be desirable to change the order in which the outer strands of yarn pass over and under the inner carriers, to thereby vary the form of braid produced. Another feature of the invention therefore resides in the construction whereby the position of the actuating pins may be readily varied to change the order in which the noses are tilted.

Still another feature of the invention resides in the construction of the outer yarn carriers that support the outer yarn masses.

Other features of the invention and novel combination of parts in addition to the above will be hereinafter described in connection with the accompanying drawings which illustrate one good practical form of the invention.

In the drawings:—

Fig. 1 is a perspective view of a braiding machine constructed in accordance with the present invention.

Fig. 2 is an enlarged perspective view of the inner yarn carriers and other parts of 60 the braiding machine of Fig. 1.

Fig. 3 is a face view of one of the outer yarn carriers.

Fig. 4 is a face view of a portion of the outer revolving drum, showing two operating pins in section.

Fig. 5 is a vertical sectional view of portion of the machine of Fig. 1.

Fig. 6 is a top plan view of one of the tilting noses and associated parts, the portion of the revolving drum that supports a pin being broken away, and 70

Fig. 7 is a diagrammatic view of the inner wall of the revolving drum and of two inner carriers.

The machine frame for supporting the braiding elements may be of any usual or desired character suitable for this purpose, and as shown comprises a series of upstanding supports or legs 10 which support the 80 table 11. The table 11 is provided with a central fixed drum or core 12, which, in the present instance, is shown as having an inner diameter much larger than the diameter of the braid. The central fixed drum 85 12 is supported by arms 13 extending inwardly from the annular table 11.

An outer revolving drum 14 is supported to rotate about the fixed drum 12 and the revolving drum 14 has a laterally extending flange portion 15 which forms a connection between the cylindrical portion of the drum 14 and its hub 16. Upon the upper edge of the outer revolving drum 14 is mounted a ring 17 which is insulated 95 from the drum by the insulating material 18 and the ring 17 has a downwardly extending annular flange 19.

Upon the upper face of the ring 17 are mounted the frames 20 that form the outer 100 yarn carriers, and each frame 20 is constructed to support a yarn mass 21, the arrangement being such that these carriers are supported by and rotate with the outer revolving drum 14. Each outer yarn carrier 20 is shown as consisting of a base plate 22 which may be secured to the upper face of the ring 17 by screws 23 and the base plate is provided with uprights 24 which are spaced a sufficient distance apart to 105 110

receive the yarn mass 21 between them. The uprights 24 are conveniently formed integral with the base 22 and are provided with the laterally extending arms 25 in the 5 upper face of which is formed a notch 26 adapted to receive an end of the spindle that supports the yarn mass 21, the arrangement being such that the ends of the spindle of the yarn mass may be readily dropped in 10 the slots 26 to mount the yarn mass upon its carrier, and may be easily lifted out of these slots to remove the yarn mass. The upper ends of the uprights 24 are connected by a bridge bar 27 which is conveniently formed integral with the uprights, and the bridge bar is provided with spaced upwardly extending ears 28 that serve to limit the travel of the yarn 29 back and forth along the upper edge of the 20 bridge bar, as it unwinds from the yarn mass. The base plate 22 is conveniently provided with spaced lugs 30 adapted to support a flexible blade 31 the upper end of which is held in yielding engagement with the yarn mass 21 to prevent the yarn from unwinding too freely.

In the construction shown, the inner yarn carriers 32 are supported to revolve about the axis of the braiding machine within the 30 revolving drum 14 and each inner yarn carrier 32 consists of a hollow frame having a central opening adapted to receive the inner yarn mass 33. The inner end of each inner yarn carrier 32 is supported by a 35 roller 34 adapted to rest upon the track 35 formed upon the upper face of the hub 36 of the fixed gear 37. This gear is rigidly secured to the upper end of the central fixed drum or core 12, and a set screw 38 or 40 other means may be provided for rigidly securing the hub 36 of this gear to the drum 12.

The means for supporting the outer ends 45 of the inner carriers 32 may be variously constructed, and in the present case each of the inner carriers is shown as provided at its outer end with a pair of spaced shoes 39 adapted to extend into an annular groove 40 formed in the inner face of the outer revolving drum 14. These shoes are 50 conveniently mounted in slots formed in the frame 32 and may be secured in place by bolts 41, and the shoes 39 are adapted to slide smoothly in the slot 40 as the inner carriers travel about the axis of the braiding machine.

Various means may be provided for driving 60 the inner carriers and in the construction shown, means to this end consists of an annular driving frame 42 the hub 43 of which is rigidly secured to an inner revolving drum 44 mounted to rotate about the fixed central drum or core 12, and the means for rotatably supporting the inner revolving 65 drum 44 consists of anti-friction balls

45 which lie in an annular groove formed in the upper face of a laterally extending portion 46 of the central core 12 and the upper portion of these balls is received in an annular groove formed in the under face of 70 an annular flange 47 of the drum 44.

In the construction shown, the inner revolving drum 44 rotatably supports the outer revolving drum 14, and to this end the hub 16 of the outer revolving drum is 75 journaled upon the outer cylindrical portion of the inner drum 44 and the weight of the drum 14 is supported by an annular flange portion 48 of the inner revolving drum, which flange portion extends upwardly from the laterally extending portion 49 provided at the lower end of the inner revolving drum 44. Anti-friction balls 50 are provided between the upper face of the upstanding portion 48 and the under face of the outer revolving drum and form 80 an anti-friction bearing for supporting the revolving outer drum 14.

In order to rotate the outer revolving drum 14 and the driving frame 42 for the inner carriers in opposite directions, the outer revolving drum 14 is provided with a ring gear 51 rigidly secured to its under face by bolts 52, and the inner revolving drum 44 is provided with a similar ring gear 53 which is bolted to the flange portion 49 of the inner revolving drum below and in spaced relation to the ring gear 51. A bevel gear 54 positioned between these two ring gears, and rigidly secured to the driving shaft 55, serves to rotate these ring gears in opposite directions, so that the outer revolving drum is rotated in one direction while the driver 42 for the inner carriers is rotated in the opposite direction. 105

In order to impart the rotative movement of the driver frame 42 to the inner carriers, in the construction shown, each inner carrier is provided at its under face with a bearing block 56 having a concave bearing surface adapted to receive a rotating driving disk 57, there being a driving disk for each inner carrier, and each of these disks is mounted upon and is rotated by its shaft 58 journaled in a bearing block 59 secured to the driver frame, and at the inner end of each shaft 58 is provided a bevel gear 60 that meshes with the teeth formed in the under face of the fixed gear 37. As a result of this construction, rotation of the driver frame 42 will cause the disks 57 to drive the inner carriers and will also positively rotate the driving disks 57 to facilitate the passage of the strands of yarn 29 between the disks 57 and cooperating blocks 56 as the inner carriers pass over the strands of yarn. Each driving disk 57 is preferably provided with a number of notches 61 adapted to receive the strand of yarn 29 as the strand passes between the disk and block. 130

The notched driving disk 57 and cooperating block 56 not only forms a driving means for the inner carriers which positively controls the movement of the inner carrier, but may serve also to support the weight of the inner carrier, so that the sliding shoes 39 may run more freely in the annular groove 40.

The means so far described for supporting and driving the inner carriers do not form a part of the present invention and it should be understood that the means now to be described for directing the outer strands of yarn over and under the inner carriers may be employed upon various different types of braiding machines.

As stated, the present machine does not employ the traversing arms commonly used heretofore to raise and lower the outer strands of yarn, and the outer strands of yarn 29 from each yarn mass may therefore be led from the bridge bar 26 of an outer yarn carrier downwardly thru a hole 62 in the ring 17, and then about a suitable guide 25 which may constitute a round bar or ring 63 which surrounds the outer revolving drum 14 and is held in spaced relation to the outer wall of this drum by brackets 64. The strands of yarn 29 pass from the bar 63 thru vertical slots 65 formed in the outer revolving drum 14 and then to the braiding point, determined by the position of the lower end of the central guide sleeve 66.

Each inner carrier 32 is provided at its outer end with a relatively long guide plate 67 which may have a central opening adapted to fit the outer end of the inner carrier 32, as will be apparent from Fig. 5, and this guide plate may be rigidly secured to the inner carrier by providing the guide plate with laterally extending ears 68 which may be secured to the frame 32 by the bolts 41 that hold the slides 39 in place. The width of the guide plates 67 is such that it will cooperate with the guide plates 69 at the inner end of the inner carrier, so that the guide plates 67 and 69 will hold the strands of yarn 29 out of engagement with the inner yarn mass 33 and guides upon the inner carrier.

Upon the forward end of each guide plate 67 is pivotally mounted a tilting nose 70, the same being pivotally secured to the guide plate by the pivot pin 71, and the rocking movement of each tilting nose may be limited by a pin 72 which projects into a slot 73 formed in the guide plate. Each tilting nose is pointed as shown and is positioned upon the guide plate so that when its pointed nose is tilted downwardly it will project under an outer strand of yarn 29 stretched from the guide ring 63 to the braiding point, and will direct this strand of yarn over the guide plate 67, while if the end of the tilting nose is pointed upwardly it will

pass over such strand and will direct the same under the guide plate 67.

Different constructions might be provided for shifting the tilting nose 70, and in the construction shown the means for shifting the tilting nose of each inner carrier consists of a series of pins 74 mounted in the wall of the outer revolving drum 14 below the annular groove 40 of the drum, and of a second series of pins 75 mounted in the wall of the revolving drum above the annular groove 40. The inner ends of these pins project into the path traveled by the tilting noses 70, and serve to shift each tilting nose, as will be apparent from Fig. 7. It is important that each tilting nose be tilted to the desired position before it reaches an outer strand of yarn 29 extending thru a vertical slot 65, and each of the pins 74 and 75 is therefore located sufficiently near to a slot 65 to insure that the point of the tilting nose will be properly positioned as it passes such slot.

In some cases it may be desirable to vary the order in which the inner carriers pass over and under the outer strands of yarn and the pins 74 and 75 are therefore shown as slidably mounted in the wall of the revolving drum 14 so that each pin may be supported in either an operative or inoperative position, and a pair of pins is preferably mounted adjacent each slot 65 so that either pin may be moved to its operative position in order that each tilting nose may be shifted either up or down as it approaches a particular slot, depending upon the type of braid it is desired to form.

Simple means is provided for holding each pin in either its operative or inoperative position, and consists of the bent wires 76 secured to the outer wall of the drum 14 by screws 77 and these wires have spaced resilient legs adapted to engage either one of a pair of annular grooves formed on each pin so that these resilient legs will snap into one groove or the other to hold the pins 74 and 75 in the desired position.

It is found that in the various types of braiding machines employing inner and outer yarn carriers, the strands of yarn which are stretched from a point outside of the outer revolving drum to the braiding point tend to vibrate rapidly. This vibration is in many cases undesirable, and is particularly objectionable when the yarn being braided is formed of asbestos or other relatively heavy material having low tensile strength, as the vibrations may cause the yarn to break. In the present construction this undesirable vibratory movement is prevented, and to this end each guide plate 67 is made relatively long so that one guide plate will remain in engagement with a strand of yarn 29 and hold the same from vibrating until the tilting nose of the next guide plate is

5 nearly in position to engage the strand of yarn, and as a result the interval of time which elapses while a particular strand of yarn is not engaged by a guide plate is so short that it does not have time to vibrate appreciably. In this manner each strand of yarn 29 is caused to remain practically still during the short interval of time which elapses while it is not engaged by a guide 10 plate, and since the inner yarn carriers revolve rapidly in one direction, and the outer yarn carriers revolve rapidly in the opposite direction, the period of time which elapses while one guide plate moves out of engagement with the strand of yarn, and the nose of the next guide plate moves into engagement with the same is extremely short.

15 The outer strands of yarn are necessarily more or less elastic and the tension maintained upon these strands should be such that they may be displaced laterally by the guides 67 and 69 to permit the inner carrier to pass, but will return to the normal straight line position as soon as they are 20 clear of an inner carrier.

25 In order to drive the braiding machine, the main operating shaft 55, which has the bevel gear 54 secured to its inner end, is driven by a belt pulley 78, and a clutch 79 that is controlled by the hand-operated lever 80 serves to start and stop the braiding machine, as is usual. The operating clutch is urged to its shaft driving position by the tension spring 81 and the lever 80 is held 30 in its driving position by latch mechanism not shown, but which is controlled by the solenoid 82, the arrangement being such that when the electric current is supplied to the solenoid the lever 80 will be released to 35 stop the braiding machine in a well known manner. Current may be supplied to the braiding machine by the conductor wires 83 one of which leads to a switch 84 which is normally open to cut off the supply of current to the braiding machine, but which is 40 under the control of the lever 80, so that when the lever is moved to the machine operating position, an extension 85 upon this lever serves to hold the switch closed. 45 As a result of this construction electric current will be supplied to the braiding machine only when this machine is being operated, which is desirable.

50 In the construction shown, electric current is supplied to the ring 17 which is insulated from other parts of the braiding machine by a contact brush 86 and the brush is insulated from and is supported by a fixed arm 87 extending upwardly from a fixed 55 ring 88 mounted upon the frame 11. As the outer revolving drum 14 rotates the contact brush 86 will slidingly engage the outer edge of the ring 17 to supply current to the same. In order that the current may 60 pass from the insulated ring 17 to the stop

65 mechanism 89 of the inner carriers, each inner carrier has a contact brush 90 which is held in sliding engagement with the inner face of the downwardly extending flange portion 19 of the ring 17. The other portions of the braiding machine may be grounded as usual, so that when the electric stop mechanism 89 of the inner carriers is 70 permitted to close the circuit between the insulated ring 17 and grounded portions of 75 the braiding machine, the circuit will be completed to actuate the solenoid 82 and stop the braiding machine in a well known manner.

80 The sleeve 66 which determines the braiding point may be supported by a fixed arm 91 and the completed braid is shown as passing upwardly to the take-up mechanism 92, which may be of any usual or preferred construction. An indicating device 93, of 85 any well known construction, may be held in engagement with the completed braid 94 to indicate the amount of braid produced.

85 Each outer strand of yarn 29 may be lead thru the eye of a stop lever 95 which is 90 pivotally mounted at 96 upon the outer revolving drum 14 in position to swing downwardly under the force of gravity to close the electric circuit when an outer strand breaks or becomes too slack. 95

What is claimed is:

1. In a braiding machine, in combination, outer and inner yarn carriers, means for revolving the carriers in opposite directions, tilting noses pivotally mounted on the inner carriers in position to engage the strands of yarn passing inwardly from the outer yarn carriers, and abutments supported independently of the inner carriers and in the path of travel of the tilting noses to engage 100 and tilt the noses and cause them to direct the outer strands of yarn alternately under and over the inner carriers. 105

2. In a braiding machine, in combination, means for supporting a series of outer yarn 110 carriers and for guiding the outer strands of yarn inwardly to the braiding point, means for supporting and revolving a series of inner yarn carriers, tilting noses mounted upon the inner yarn carriers, projections supported independently of the inner yarn carriers in position to contact with and shift the tilting noses as the projections and inner carriers pass each other to direct the outer strands of yarn alternately over 115 and under the inner yarn carriers. 120

3. In a braiding machine, in combination, an outer revolving drum, outer yarn carriers mounted upon said drum, inner yarn carriers, means for revolving the outer and inner yarn carriers in opposite directions, tilting noses pivotally mounted upon the inner carriers, and pins mounted upon the revolving drum in the path of travel of the 125 tilting noses and adapted to engage the 130

noses and shift them to direct the outer strands of yarn either under or over the inner carriers.

4. In a braiding machine, in combination, an outer revolving drum provided with vertical slots thru which the strands of outer yarn pass to the braiding point, outer yarn carriers mounted upon said drum, inner yarn carriers, means for supporting and revolving the inner yarn carriers, a tilting nose upon each inner yarn carrier, and pins carried by the outer revolving drum adjacent said vertical slots and adapted to engage the tilting noses and shift them as the pins and inner carriers pass each other to direct the outer strands of yarn either over or under the inner yarn carriers.

5. In a braiding machine, in combination, an outer revolving drum provided with vertical slots thru which the strands of outer yarn pass to the braiding point, outer yarn carriers mounted upon said drum, inner yarn carriers, means for supporting and revolving the inner yarn carriers, tilting noses upon the inner yarn carriers for directing the outer strands of yarn over or under the inner carriers, and means carried by the outer revolving drum to project into the path of travel of the tilting noses and adapted to tilt the noses and positively hold them in their tilted position as the noses approach said slots.

6. In a braiding machine, in combination, outer and inner yarn carriers, means for revolving the carriers in opposite directions, tilting noses mounted upon the inner carrier in position to engage the strands of yarn passing from the outer yarn carriers to the braiding point to direct the strands over or under the inner carriers, pins supported independently of the inner carriers in position to engage and shift the tilting noses, and means for supporting the pins in different arrangements to thereby vary the braiding operation of the braiding machine.

7. In a braiding machine, in combination, an outer revolving drum provided with vertical slots thru which the strands of outer yarn pass to the braiding point, outer yarn carriers mounted upon said drum, inner yarn carriers, means for supporting and revolving the inner yarn carriers, tilting noses upon the inner yarn carriers for directing the outer strands of yarn over or under the inner carriers, pins supported by the revolving drum in position to engage and shift the tilting noses, and means for supporting the pins in different positions so that each nose will be tilted up at a particular slot under one adjustment of the pins, or down at that slot under another adjustment of the pins to vary the braiding operation.

8. In a braiding machine, in combination, an outer revolving drum provided with

vertical slots thru which the strands of outer yarn pass to the braiding point, outer yarn carriers mounted upon said drum, inner yarn carriers, means for supporting and revolving the inner yarn carriers, tilting noses upon the inner yarn carriers for directing the outer strands of yarn over or under the inner carriers, and a pair of pins mounted upon the revolving drum adjacent each slot and movable independently to and from the nose tilting position so that if one pin is adjusted to its operative position it will tilt the noses to pass under the strand of yarn passing thru said slot and if the other pin is adjusted to the operative position the nose will pass over the strand of yarn.

9. In a braiding machine, in combination, an outer revolving drum, having an annular groove formed in its inner wall, outer yarn carriers mounted upon said drum, inner yarn carriers supported to travel about the axis of the braiding machine within said drum, means for revolving the outer and inner carriers in opposite directions, projections upon the inner carriers extending into said annular groove, tilting noses upon the inner carriers for directing the outer strands of yarn under and over the inner carriers, and pins extending inwardly from the inner wall of said drum upon the opposite sides of the annular groove to shift the noses.

10. A yarn carrier for the outer yarn mass of a braiding machine, comprising an integral frame of cast metal having a supporting base, uprights extending upwardly from the base and spaced to receive a yarn mass between them and each having a slot for receiving an end of the spindle upon which the yarn mass is mounted, and a bridge bar connecting the upper ends of the uprights and having spaced ears upon its upper face to limit the travel of the yarn along the upper face of the bridge bar as the yarn unwinds from the yarn mass.

11. A yarn carrier for the outer yarn mass of a braiding machine, comprising a base plate, uprights extending upwardly from the base plate and spaced to receive a yarn mass between them, a bridge bar connecting the upper ends of the uprights and having spaced ears for limiting the travel of the yarn along the bridge bar as the yarn unwinds from the yarn mass.

12. A yarn carrier for the outer yarn mass of a braiding machine, comprising a base plate, uprights extending upwardly from the base plate and spaced to receive a yarn mass between them, a bridge bar connecting the upper ends of the uprights, projections upon the base plate, and a spring tension plate supported by said projections to bear against the yarn mass.

13. In a braiding machine, in combina-

tion, outer and inner yarn carriers, means for revolving the carriers in opposite directions, tilting noses pivotally mounted on the inner carriers in position to engage the strands of yarn passing inwardly from the outer yarn carriers, and pins supported independently of the inner carriers to extend

into the path traveled by the tilting noses to engage and tilt the noses and cause them to direct the outer strands of yarn alternately over and under the inner carriers. 10

In testimony whereof, I have signed my name to this specification.

OTTO A. FREDERICKSON.
